CIGARETTE TRANSFER MACHINE

Willi Wachsmuth, Hamburg-Bergedorf, Germany, assignor to Kurt Korber & Co. K. G., Hamburg-Bergedorf, Germany

Application May 16, 1955, Serial No. 508,545

Claims priority, application Germany May 14, 1954

4 Claims. (Cl. 198—24)

The invention relates to cigarette making machines and particularly to a device for ejecting any desired number of cigarettes or the like from a conveyor chain which is continuously in motion and is provided with transverse grooves in which the cigarettes are positioned. The cigarettes are transferred to a track arranged at a right angle with respect to the conveyor chain by means of a slidable member which is attached to a guide arranged at an angle with respect to the lengthwise direction of the conveyor chain and is moved in such a manner that a relatively large pushing surface of the sliding member extends parallel to the path of movement of the conveyor chain. When this sliding member is actuated, its flat surface engages the cigarettes at right angle to the movement of the conveyor chain and at the same time the slidable member is also moved in the direction of the conveyor chain. Furthermore, the slidable member performs—in addition to this back and forth movement—another movement in a direction upwardly and downwardly with respect to the conveyor chain. This movement is performed in such a manner that at the beginning of the pushing movement toward the conveyor chain, the slidable member is moved downwardly in order to extend into the grooves of the conveyor chain, while at the end of the advancing movement the slidable member is moved upwardly away from the conveyor chain so that during the following rearward movement of the slidable member, the conveyor chain is not at all engaged thereby.

It is an object of the invention to solve the problem of effecting a quick and secure removal of the cigarettes from the grooved conveyor chain whereby at the same time by means of a single drive mechanism the entire operation is substantially simplified, particularly in such cases when it should become desirable to eject a different number of cigarettes from the grooved conveyor chain. The construction of the device of the invention is not only simple but also very economical.

It is known to employ two cam drives in machines of the mentioned type—one for controlling the back and forth movement, while the other cam drive controls the up and down movement of the slidable element which ejects the cigarettes from the conveyor chain. When these machines operate rather slowly, as is the case in conventional machines of this type, these two cam drives operate satisfactorily, but when the machines are to be operated at higher speed, then these cam drives encounter difficulties. Furthermore, the control and adjustment of the two mentioned cam drives is complicated when a different number of cigarettes is to be ejected.

It is an object of the present invention to overcome the disadvantages of the well-known devices, and, therefore, the present invention proposes to employ for the back and forth movement and for the up and down movement of the slidable ejecting member a single crank slide device which is driven by a pair of elliptical gears or by a pair of circular gears, the latter of which are eccentrically journaled so that the entire drive mechanism is rotatable

2

about the pivot point of the crank arm of the crank slide device. The up and down movement of the slidable ejecting member is controlled by a roller which is coaxially arranged with respect to the crank drive roller, whereby

5 the last mentioned roller moves along a cam plate which is rotatably connected with the slidable ejecting member. By rotating the entire drive mechanism about the pivot point of the crank arm of the crank slide drive, it is possible to eject a different number of cigarettes from the 10 grooves of the conveyor chain without the necessity of exchanging, for instance, a machine element. It is only necessary to replace the head of the slidable ejecting member by another head which corresponds in size to the 15 number of cigarettes to be ejected from the conveyor chain.

The drawing illustrates by way of example an embodiment of the invention.

Fig. 1 is a plan view of the device,

Fig. 2 shows a side elevation of a portion of the device, 20 partly in cross-section, and

Fig. 3 is a partial plan view with portions broken away to show a section on line III—III of Fig. 2.

In the drawing, a frame 1 is supported by any suitable means (not shown) and provided with a pair of parallel 25 guide rods 2 secured to a pair of upstanding flanges on said frame 1. A cross-head, or carriage 3 is slidably mounted on said rods 2 and, on its lower side, said carriage 3 is provided with a recess 11 that extends transversely of said rods 2 entirely below the same.

30 A horizontal disc 5 is rotatably mounted in the frame 1 below the rods 2 and, adjacent its periphery, provided with a vertical pin 25 to which the inner rings of two ball bearings 4 and 16 are fixedly secured. The outer ring of the upper ball bearing 4 is secured to a block 10 that is 35 slidably mounted in the recess 11 in the carriage 3. The outer ring of the lower ball bearing 16 is freely rotatable.

In a bearing 26 on the top side of the carriage 3, a horizontal shaft 19 is rotatably mounted and on one end of said shaft 19 a bell crank 18, 20 is fixedly mounted

40 with the arm 20 of said bell crank extending substantially horizontally above the top surface of the carriage 3. A bolt 24 is mounted in the end portion of said arm 20 with its free end towards the top surface of the carriage 3 and surrounded by a compression coil spring 21 having 45 one end in engagement with the arm 20 and the other end in engagement with carriage 3.

The other arm 18 of said bell crank extends downwardly at the side of the carriage 3 and has securely attached to its lower end a cam plate 17 the cam face 22,

50 22a of which is in a position to be engaged by the outer ring of the ball bearing 16 in certain positions of the parts, as described below. At least the straight portion 22 of the cam face is curved in vertical cross-section as indicated by the double line representing said straight portion 22. An adjustment screw 23 is provided in said arm 18 for a purpose to be explained below.

A rod 12 is non-rotatably secured to the opposite end of the shaft 19 and carries, at its free end, an ejector member 14 positioned adjacent and on a slightly higher 60 level than a conveyor 13 provided with transverse grooves for supporting cigarettes 27, one in each groove. Adjacent said conveyor 13, on the opposite side thereof from the device described above, is a track 15. Both said conveyor 13 and said track 15 may be parts of a cigarette 65 machine (not shown).

The disc 5 is secured to a shaft 28 which is rotatably mounted in the frame 1 and carries, on its lower end, a gear 6 also secured to said shaft 28. The gear 6 meshes with a gear 7 mounted on a shaft 7a which supports an 70 eccentrically mounted circular gear 8 driven continuously by a gear 9 that is eccentrically mounted on a shaft 9a,

The frame 1 is adjustable on its support (not shown) to different angular positions on the axis A of the shaft 28. In the present example, the angular position of the frame is such that the angle between the rod 12 and the path of movement of the conveyor 13 is 36° which is a suitable angle in the present case when the width of the ejector member 14 corresponds to a portion of the conveyor 13 containing ten grooves for ten cigarettes. In cases where said width of the ejector member is less, corresponding to a smaller number of cigarettes, a shorter ejector member is substituted and the abovementioned angle is increased by adjustment of the angular position of the frame 1 on the axis A.

In operation, disregarding for the moment the influence of the eccentrically mounted gears 8 and 9, the disc 5 is rotated continuously and the conveyor 13 is moving continuously as indicated by the arrows in Fig. 1. Obviously, the block 10 is thereby forced to move back and forth in the recess 11 while the carriage 3 is forced to move back and forth on the rods 2.

In the movement of the carriage 3 towards the conveyor 13, the ejector member 14 engages the ends of ten cigarettes and, while moving along with the conveyor, pushes said ten cigarettes out of their grooves in the conveyor 13 onto the track 15. At the end of this movement (approximately in the position shown in Fig. 1), the relative position of the ball bearing 16 and the cam plate 17 is as shown in full lines in Fig. 3. In this position, the ball bearing 16 has just come into engagement with the inclined portion 22a of the cam face 22, 22a on the cam plate 17. Continued movement of the ball bearing 16 along said inclined cam face portion 22a causes the shaft 19 with the bell crank 18, 20 and the cam plate 17 to turn on the axis of said shaft 19 in a clockwise direction as seen in Fig. 2 against the action of the spring 21. Said turning movement continues until the ball bearing 16 reaches the end of the inclined cam face portion 22a and causes the ejector member 14 to be raised to a level where it can pass freely above the conveyor 13 and the cigarettes thereon in the return stroke of the ejector member 14.

As the carriage 3 and the shaft 19 continue their movement as a unit on the rods 2, the ball bearing 16 moves along the cam face 22 towards the right in Fig. 3 and when the carriage 3 reaches the position 3' the cam face 22 is in the position 22' as indicated by dotted lines in Fig. 3. In other words, due to the above described turning of shaft 19 the cam plate 17 is lagging behind the carriage 3 a distance equal to the difference between M and N during the movement of the ball bearing 16 approximately from its top position to its bottom position as seen in Fig. 3. In the meantime the block 10 completes the righthand half of its stroke, as seen in Fig. 1. While said block 10 completes the lefthand half of its stroke, as seen in Fig. 1, and the ball bearing moves approximately from its bottom position to its top position, as seen in Fig. 3, the ball bearing is obviously out of engagement with the cam plate 17 and the relative position of the carriage 3 and the cam plate 17 is as indicated in full lines in Fig. 3. The ejector member 14 is then, again, in its lower

operational position which is adjustable by means of the screw 23 in an obvious manner. The bolt 24 is adjustable to limit the upward movement of the ejector member 14 and it is evident that said limit should be somewhat beyond the point to which said ejector member 14 is actually raised by the action of the ball bearing 16 on the cam face 22.

The function of the eccentrically mounted gears 8, 9 is to enable variation of the rotational velocity of the disc 5 while the drive source and the shaft 9a are rotating with uniform speed, as is well known in the art of power transmission. Elliptical gears are, of course, mechanical equivalents of the eccentrically mounted circular gears 8, 9 and could be used for the same purpose.

What I claim is:

1. Means for transferring cigarettes from transverse grooves in a continuously moving horizontal conveyor onto an adjacent receiving band, comprising horizontal guide means mounted beside said conveyor and forming an acute adjustable angle with the trailing end portion thereof, a cross-head slidably mounted on said guide means, bearing means in said cross-head having its axis horizontal and perpendicular to said guide means, a shaft rotatably mounted in said bearing means, ejector means non-rotatably secured to said shaft and extending toward said conveyor in a position to simultaneously engage one end of a plurality of cigarettes disposed in said conveyor grooves, lever means non-rotatably secured to said shaft and provided with a cam surface, guide surface means on said cross-head extending transversely of said guide means, disc means mounted adjacent said guide means for rotation on a vertical axis, first means eccentrically mounted on said disc means for engagement with said guide surface means, and second means eccentrically mounted on said disc means for engagement with said cam surface, whereby rotation of said disc means causes reciprocation of said cross-head with said ejector means on said horizontal guide means during simultaneous sliding back and forth of said first eccentrically mounted means on said guide surface means and intermittent turning of said shaft to raise said ejector means through engagement of said second eccentrically mounted means with said cam surface.
2. Means as in claim 1, in which said first and second eccentrically mounted means comprise two rollers concentrically and rotatably mounted on a pin projecting from said disc means at a distance from the center thereof.
3. Means as in claim 1, in which said lever means comprises a bell crank, one arm of which carries said cam surface while the other arm carries means for adjustably limiting the turning movement of said shaft and for biasing said shaft in the direction corresponding to engagement between said ejector means and the cigarette ends.
4. Means as in claim 1, including a pair of eccentrically mounted interengaging circular gears interposed between said disc means and a drive means.
